UNITED STATES PATENT OFFICE.

RALPH C. ERSKINE, OF STAMFORD, CONNECTICUT, ASSIGNOR TO ERSKINE-DANFORTH CORPORATION, A CORPORATION OF NEW YORK.

DESIGN FOR A CUPBOARD OR SIMILAR ARTICLE.

Application filed November 30, 1925. Serial No. 15,578. Term of patent 7 years.

To all whom it may concern:

Be it known that I, RALPH C. ERSKINE, a citizen of the United States, residing at Stamford, in the county of Fairfield, State of Connecticut, have invented a new, original, and ornamental Design for Cupboards or Similar Articles, of which the following is a specification, reference being had to the accompanying drawing, forming part thereof.

The figure is a perspective view of a cupboard or similar article showing my new design.

Referring to this drawing, the dominant feature of my design resides in the construction of the lower portion of the cupboard. What may be termed the body of the cupboard, that is, the portion thereof containing drawers or the like, and supporting the upper shelf-containing portion, does not extend to the floor but rests upon an open frame-work.

I claim:

The ornamental design for a cupboard or similar article as shown and described.

RALPH C. ERSKINE.
